United States Patent

Des. 238,796

Patented Feb. 10, 1976

238,796

TOY PROJECTOR

Charles A. Cummings and Gerald M. Rodmaker, Cincinnati, Ohio, assignors to General Mills Fun Group, Inc., Minneapolis, Minn.

Filed Feb. 4, 1974, Ser. No. 439,518

Term of patent 14 years

Int. Cl. D21—01

U.S. Cl. D34—15 R

FIG. 1

FIG. 2

FIG. 3

FIG. 4

FIG. 5

FIG. 9

FIG. 1 is a front perspective view of a toy projector embodying our new design;

FIG. 2 is a rear perspective view thereof;

FIG. 3 is a top plan view thereof;

FIG. 4 is a left side elevational view thereof;

FIG. 5 is a bottom elevational view thereof;

FIG. 6 is a right side elevational view thereof;

FIG. 7 is a front elevational view thereof;

FIG. 8 is a sectional view taken on the line 8—8 of FIG. 6; and

FIG. 9 is a rear elevational view thereof.

We claim:

The ornamental design for a toy projector, substantially as shown and described.
